UNITED STATES PATENT OFFICE.

CLARENCE A. BEALL, OF SATICOY, CALIFORNIA, ASSIGNOR OF ONE-THIRD TO EDWARD C. BARKSTROM, OF LOS ANGELES, CALIFORNIA.

BILLBOARD AND PROCESS FOR REMOVING POSTERS FROM BILLBOARDS.

Application filed March 16, 1925. Serial No. 15,914.

To all whom it may concern:

Be it known that I, CLARENCE A. BEALL, a citizen of the United States, residing at Saticoy, in the county of Ventura and State 5 of California, have invented a new and useful Billboard and Process for Removing Posters from Billboards, of which the following is a specification.

This invention relates to method and apparatus for removing paper, fibre or other material from bill boards or walls which paper, fibre or other material has been secured to the bill board or wall by adhesive paste, mucilage or like material.

At the present time bill posting companies are put to a large expense in order to remove old posters from bill boards or the like as by the bill boards and methods of removing bills from the same now in use the old posters must be removed by tearing, scraping and washing from the outside of the posters before a new poster may be applied. This requires a considerable time and large expense for labor, the old paper being removed 20 in scraps making a dirty operation and requiring additional time for cleaning up the old paper from around the bill board.

It is an object of the present invention to provide a method and apparatus by which 30 old posters or the like may be removed from bill boards with a less expenditure of labor and by which the old posters may be removed in large pieces or in toto therefrom to the end that the expense and loss of time 35 of the present tearing and scraping methods may be largely eliminated.

In carrying out the present invention the old posters or the like are attacked first from the rear in place of from the front surface 40 of the board by a material usually hot water or wet steam adapted to disintegrate or dissolve the adhesive paste, mucilage or other material holding the poster to the board with the result that the old poster may be 45 bodily removed from the board without the present tearing and scraping procedure.

Various objects and advantages of the invention will best be understood from a description of the preferred example of a method 50 and apparatus embodying the invention, for which purpose reference is made to the accompanying drawings in which a preferred form or example of an apparatus embodying the invention is disclosed and by 55 which apparatus a preferred method of re-

moving old posters or the like may be carried out.

In the drawings:

Figure 1 is a front elevation of a bill board or apparatus for removing posters 60 therefrom embodying the invention.

Fig. 2 is a fragmentary elevation at right angles to Fig. 1 mainly in vertical section.

Fig. 3 is a view similar to Fig. 2 of a slightly modified form of the invention, and

Fig. 4 is a fragmentary front elevation of the form of the apparatus shown in Fig. 3.

Referring to the drawings, 2 indicates the usual customary plate or supporting wall of

a bill board preferably secured to a wooden 70 backing 3 and surrounded by a frame 4. In

order that the present method of removing posters from the bill board could be carried out and that such ordinary bill board may be converted to an apparatus embodying the 75

present invention there is placed in front of such plate 2 a perforated plate 5 preferably of similar dimensions to that of the plate 2 and having a large number of equally spaced

perforations 6. The perforated plate 5 is 80 preferably held slightly in front of the normal plate 2 of the bill board by suitable

means such as spacers 7 to form therebetween a chamber 8 for distribution of an adhesive disintegrating agent. There is also 85

connected to the chamber 8 a number of small chests 9 at the rear of the bill board, all of which are preferably connected together by pipes 10 so that they may be supplied

with an agent adapted to disintegrate the 90 adhesive employed to hold the posters to the bill board from a common point.

In use the posters 11 are secured to the front surface of the perforated plate 6 by 95 paste or mucilage or any other preferred form of material.

When it is desired to remove the same to place a new poster upon the board such posters 11 may then be removed without requiring the usual tearing

and scraping through introducing an agent 100 adapted to disintegrate the adhesive holding

the poster 11 to the plate 5, this agent being passed through pipes 10 and chest 9 and distributed throughout the chamber 8 so that

it may pass through the perforations 6 of 105 the perforated plate 5 and effectively disintegrate the adhesive holding the poster 11 to said plate 5.

With ordinary paste or mucilage wet steam or hot water is preferably 110 employed. The wet steam may be supplied

from any portable steam boiler. When introduced into the chamber 8 it will soak the adhesive holding the poster 11 to the perforated plate 6 and the old poster may then be readily removed in large pieces.

In Figure 3 there is shown a modified form of the apparatus in which the perforated plate 5^a is held by the rear plate 2^a by lugs 7^a turned in from the perforated plate 10 5^a in forming its perforations 6^a.

While the method and apparatus for removing posters from bill boards herein described is well adapted to carry out the objects of the invention, various modifications may be made without departing from the principles of the invention and the invention therefore includes all such changes, modifications, substitutions, equivalents as come within the scope of the appended 20 claims.

I claim:

1. An apparatus of the class described, comprising a perforated poster holding

plate, means forming a chamber rearwardly of the plate, and means for introducing an agent into said chamber adapted to disintegrate the adhesive employed to retain the poster to said perforated plate.

2. An apparatus of the class described, comprising a front and rear plate spaced apart to provide a chamber therebetween the front plate being perforated and adapted to operate to hold the poster thereto by the aid of an adhesive, and means for supplying to said chamber an agent for disintegrating 30 said adhesive.

3. A bill board of the class described comprising a perforated plate, a poster secured by adhesive to one side of such perforated plate, and means for supplying to the other side of said perforated plate an adhesive 40 disintegrating material.

Signed at Los Angeles Calif. this 9 day of March, 1925.

CLARENCE A. BEALL.
